RAIL OILER

Gustav M. Osterberg, Harrington Park, N. J.

Application November 6, 1930. Serial No. 493,733

4 Claims. (Cl. 184—22)

This invention relates to oilers adapted for use in lubricating the guide rails of elevators and other apparatus arranged to move longitudinally of guide rails of any kind or class; and the object of the invention is to provide an oiler of the class specified, involving a unit body of cast material, preferably formed by die casting to eliminate milling, drilling and other machine operations, thus materially reducing the manufacturing cost of devices of the class under consideration; a further object being to provide a comparatively large, box-shaped casing forming a container for the oil or lubricant employed with a discharge passage arranged a predetermined distance above the bottom of said casing, and a multiple strand body disposed in said passage and arranged internally of the casing and also extending beyond said port for engagement with a rail to be lubricated, and further to the provision of an enlarged body disposed within the chamber of the casing in which said port is formed and the provision of an adjustment screw accessible from within the casing, controlling and regulating the discharge of oil through said passage and the strand body arranged therein; a further object being to provide, externally of the casing, a channel-shaped housing, into the central portion of which said discharge aperture opens, means being provided at the upper end of the housing for supporting a U-shaped body of fibrous material, forming a wiper for removing dust, grit or the like from the rail, facilitating the proper lubrication thereof; a further object being to provide means disposed at each side of said U-shaped housing at the lower end thereof and on the adjacent part of the casing for detachably mounting the oiler in connection with suitable supports; a still further object being to provide the lower face of the housing and adjacent part of the casing with an oil groove whereby any excess oil which may collect in said channel housing may be returned thereto and to the rail; a still further object being to provide the open end of the casing with a hinged and substantially dust-proof cover preventing grit and dust from entering the oil storage chamber of the casing to a major degree; and with these and other objects in view, the invention consists in an oiler of the class and for the purpose specified, which is simple in construction, efficient in use, and which is constructed as hereinafter described and claimed.

The invention is fully disclosed in the following specification, of which the accompanying drawings forms a part, in which the separate parts

of my improvement are designated by suitable reference characters in each of the views, and in which:—

Fig. 1 is a side, sectional view of an oiler made according to my invention, diagrammatically indicating one method of its attachment to an elevator.

Fig. 2 is a section on the line 2—2 of Fig. 1; and,

Fig. 3 is a bottom and sectional plan view of a part of the construction shown in Figs. 1 and 2.

For the purpose of illustrating one method of carrying my invention into effect, I have indicated at 5 in Fig. 1 of the drawing, a part of the top portion of an elevator, and at 6 one of the guide rails of the elevator. At 7 I have shown two brackets or other supports on the elevator disposed at opposite sides of the rail 6 or the flange 6a thereof, upon which one of my improved rail oilers is adapted to be supported.

In the construction shown, the oiler consists of a unitary casing 8, which is preferably rectangular or box-shaped in form, and may be cast or molded in any desired manner, but is preferably molded from die cast material so as to avoid the necessity of drilling, reaming or otherwise finishing the product. The casing has a comparatively large storage chamber 9 for oil or other lubricant, and the capacity of this chamber will govern the particular type of installation which is made, depending largely upon the distance travelled by the elevator. This chamber may have a capacity of from one pint of lubricant, to any desired number of quarts.

Formed integrally with one side wall 8a of the casing 8 and arranged within the chamber 9 thereof is an enlarged body 10, which is also integral with the bottom wall. Adjacent the upper end of the enlargement 10 is formed a transverse oil discharge port 11, opening into the chamber 9 and outwardly through the wall 8a into a chamber 12 formed within a U-shaped or channel-shaped housing 13 extending outwardly through the wall 8a from the lower end of said wall to a point adjacent the upper end thereof.

Arranged in the port 11 is a wick or multiple strand body 14, the major portion of which is coiled within the bottom of the chamber 9 and one end extends into the chamber 12 and is flared therein as seen at 14a to engage the flange 6a of the guide rail 6. It will be understood that the discharge port 11 is arranged well above the bottom of the chamber 9 so that lubricating oil may be fed by gravity as well as being siphoned from said chamber due to the capillary attrac-

tion of the multiple strand body. This feature of my invention is described and claimed in two United States patents granted to me, namely, No. 1,181,538 dated May 2, 1916 and No. 1,595,548 5 dated August 17, 1926, over which the structure disclosed herein constitutes an improvement.

The discharge of the lubricating oil through the multiple strand body 14 disposed in the port 11 is controlled by an adjustable screw 15 in screw threaded engagement with the upper end 10 of the enlargement 10, the inner end 15a of the screw being conical in form and serving to engage and compress the strands of the body 14 to increase and decrease the flow or feed of the lubricant through said strands. By arranging this screw within the chamber 9, the device becomes more fool proof in that the screw is concealed from the exterior of the oiler and would be operated only by those authorized to make necessary 20 adjustments and to care for the refilling of the chamber 9. Further, this arrangement of the screw 15 prevents any possible leakage of oil that may exist upwardly around the screw from passing to the exterior of the casing, which might be 25 the case in arranging the screw externally thereof as in one of my earlier patents.

The upper ends of the side and back walls of the housing 13 are slightly enlarged and provided with grooves 16 to receive a comparatively heavy, 30 U-shaped body 17 of fibre or other relatively soft, cushioning material adapted to engage the end and side walls of the flange 6 of the rail to act as a wiper to remove grit or dirt which may collect on the rail, thus maintaining the rail in a clean and smooth state at all times. The body 17 is held in place by pins or tacks 17a 35 passed through the top of the side walls of the housing 13.

At the lower end of the side and back walls of 40 the housing 13 are inwardly extending flanges 18 which project slightly and serve to catch any drip oil that may prevail within the chamber 12. This oil or substantially most of the same will pass around the flange 18 onto the bottom 45 wall of the casing or the housing portion 13 thereof and be checked by the groove 19 encircling the side and back walls of the housing 13 or the chamber 12 therein.

At the bottom of the side wall 8 of the casing 50 and projecting outwardly therefrom and from the bottom of the side walls of the housing 13 are lug plates 21 having elongated apertures 22, note Figs. 2 and 3 of the drawing. These lugs serve as means for supporting an oiler in connection with certain 55 types of elevator apparatus, employing the supporting bracket 7, the latter being disposed beneath the lugs 21, and bolts 23 are passed through the elongated apertures 22 and through the brackets 7 to support the oiler in connection with 60 the top of the elevator. It will be understood at this time that in other types of elevator construction which do not employ the brackets 7 or their equivalent, the casing of the oiler will be constructed to suit such other types of installation.

The top of the casing 8 is open and adapted to 65 be closed by a cover plate 24 having depending flanges 25 at the sides and free end thereof, which overlap the walls of the casing, the cover 24 being hinged to the casing by hinge pins or screws 26 passed through ears 27 which overlap opposite side walls of the casing. The hinge end of the cover plate is preferably formed into a dome-shaped hood 28 which facilitates the swinging 70 movement of the cover from a closed to an open

position, the open position being indicated in dotted lines in Fig. 1 of the drawing.

With an oiler of the class specified, it will be apparent that the most efficient and positively functioning means for applying lubricant to the 80 guide rails of an elevator or other apparatus is provided, without undue waste of oil, and the lubricant operation results in the application of a thin film of oil onto the rail in the upward and downward movement of the elevator with reference thereto. 85

By providing the wiper pad of cushioning material, the rail may be kept clean and free from grit and dirt at all times, it being understood that this wiper is detachably supported in connection with the oiler and may be replaced from time to time should the same become worn or otherwise rendered useless, the wear upon this pad being slight, however, due to the fact that it is constantly 90 saturated with oil. 95

It will be understood that while I have shown certain structural details for carrying my invention into effect, that I am not necessarily limited to these details, and various other changes in and modifications of the structure herein shown 100 and described may be made within the scope of the appended claims without departing from the spirit of my invention or sacrificing its advantages.

Having fully described my invention, what I 105 claim as new and desire to secure by Letters Patent, is:

1. An oiler of the class described comprising a casing, a relatively long channel housing projecting outwardly from one side wall of the casing, 110 said side wall of the casing having a discharge port opening into the central portion of the channel of said housing and into the chamber of the casing adjacent and above the bottom thereof, and means involving a multiple strand body arranged in said passage, the chamber of said casing and in said channel for transmitting a lubricant from the chamber of said casing to that part of said strand body disposed within said channel, 115 said casing having an enlargement in the chamber centrally and adjacent the bottom of one side wall thereof and through which said discharge port passes and a screw adjustably supported in said enlargement and accessible from within the chamber of said casing, the end of said screw being adapted to enter said port to cooperate with the multiple strand body therein to control the discharge of lubricant therethrough, the inner faces of the walls of said housing adjacent the upper end thereof being grooved, and a 130 U-shaped body of fibrous material adapted to be arranged in said grooves and to engage a guide rail disposed within the channel of said housing forming a wiper to remove grit and dirt from the rail. 135

2. An oiler of the class described comprising a casing, a relatively long channel housing projecting outwardly from one side wall of the casing, 140 said side wall of the casing having a discharge port opening into the central portion of the channel of said housing and into the chamber of the casing above the bottom thereof, means involving a multiple strand body arranged in said passage, the chamber of said casing and in said channel for transmitting a lubricant from the 145 chamber of said casing to that part of said strand body disposed within said channel, the upper end of the walls of said housing being grooved to receive a U-shaped body of fibrous material adapted to engage the side and one end wall of 150

- a rail arranged in the channel of said housing, forming a wiper to remove dust and grit from the rail prior to the application of the lubricant thereto.
- 5 3. An oiler for the guide rails of elevators comprising a box-shaped casing, a U-shaped housing arranged centrally and vertically on one side wall of the casing and extending from the lower end thereof upwardly to a point below the top of 10 the casing, the casing including a passage opening centrally into said U-shaped housing and the interior of the casing adjacent the bottom thereof, a fibrous body in said casing and housing and passed through said passage for transmitting oil 15 from the casing into said housing, the lower end of said housing having inwardly extending flanges about the periphery thereof, the upper end of said housing having an enlarged inwardly extending flange, a groove formed in said flange for receiving and supporting a U-shaped body of fibrous 20 material forming a wiper for engaging the side and one end wall of a rail arranged in the channel of said housing, the lower end of the casing and housing including outwardly and laterally 25 extending apertured lugs by means of which the oiler may be supported in connection with an elevator, and the lower surface of the housing and
- casing being flush and including a groove bordering the side and back walls of said housing.
4. A rail oiler of the class described comprising a box-shaped casing open at the top and a cover controlling said opening, a channel disposed on one outer side wall thereof for receiving a rail to be lubricated, said side wall of the casing having an enlarged member projecting into the chamber of the casing and having a passage for placing said chamber in communication with said channel, a multiple strand body arranged in the chamber of said casing and extending through said passage into said channel for transmitting a lubricant from said chamber to said channel to lubricate the rail passing therethrough, a screw adjustably mounted in the upper end of said member and entering said passage for controlling the feed of lubricant through said strand body, said screw extending upwardly into the chamber of said casing and accessible solely through the open end of the casing, the walls of said channel being grooved and a U-shaped body of fibrous material arranged in the grooves of said channel and extending into the channel to engage the rail therein.
